CLAIM

The ornamental design for a tote box top rail corner piece,
as shown and described.

DESCRIPTION

FIG. 1 is a perspective view of a tote box top rail corner piece showing my design, with environment shown in phantom and not claimed as part of the invention;
FIG. 2 is a top plan view thereof;
FIG. 3 is a front elevational view thereof, the left side view
is a mirror image thereof;
FIG. 4 is a rear view thereof, the right side view is a mirror
image thereof; and,
FIG. 5 is a bottom view thereof.
